UNITED STATES PATENT OFFICE.

JOHN A. LANNERT AND WILLIAM R. JEAVONS, OF CLEVELAND, OHIO.

VAPOR-BURNER.

SPECIFICATION forming part of Letters Patent No. 556,355, dated March 17, 1896.

Application filed March 24, 1893. Serial No. 467,467. (No model.)

To all whom it may concern:

Be it known that we, JOHN A. LANNERT and WILLIAM R. JEAVONS, citizens of the United States, residing at Cleveland, in the county 5 of Cuyahoga and State of Ohio, have invented certain new and useful Improvements in Vapor-Burners; and we do hereby declare that the following is a full, clear, and exact description of the invention, which will enable 10 others skilled in the art to which it appertains to make and use the same.

Our invention consists in a novel arrangement of the parts for initially heating the burner, and also in means whereby two or 15 more burners are supplied from one vapor-jet orifice, together with other novel features of construction and combination as shown and described and particularly pointed out in the claims.

20 In the accompanying drawings, Figure 1 is a vertical central elevation of the generator. Fig. 2 is a plan view of a section of the induction end of the mixing-chamber and shows the ducts or openings to supply air thereto. Fig. 25 3 is a plan view of a stove embodying our improvements and having the top broken away to disclose the burner mechanism beneath, as hereinafter more fully described. Fig. 4 is a section on line 2 2, Fig. 3, showing the closing and regulating plate over the burner in 30 position to deflect vapor into the lighting-duct above the mixing-chamber. Fig. 5 is a cross-section on line 3 3, Fig. 3, showing the relation of the lighting-duct to the mixing-chamber and the depth and construction thereof.

35 In the drawings like letters of reference designate like parts in all the figures.

40 A is the supply-pipe for the oil or vapor, and forms a continuation of the supply-pipe from the oil-tank and serves alike for all the burners. A duct $a a$ from the upper part of the supply-pipe communicates with the valve or needle orifice a' , which is controlled by the valve a^2 having a stem convenient for the operator.

45 C is a chamber in which the vapor and entrained air are thoroughly mixed, and is designated as the "mixing" or "commingling" chamber.

50 D is a duct from the bottom of the mixing-chamber to a receptacle E formed about the base of the upright supply-pipe A and serves,

when initially starting the burner, to conduct the gasoline escaping from orifice a' to the said receptacle E. This receptacle E is in the 55 form of a deep circular trough or its equivalent and extends around the base of the upright supply-pipe A.

F is a valve controlling an orifice f at the upper end of the duct f' , which communicates below with the supply-pipe at its lower end and serves to discharge gasoline or oil into the receptacle E. The trough or receptacle E is filled with some absorbent material, such as asbestos or the like, and both the duct 65 D and valve-orifice f are in position to discharge near the top of the trough E and a little below the surface of said absorbent material, for reasons hereinafter described.

A perforated tube G is seated on the sides 70 of trough or receptacle E and extends upward and surrounds the pipe A at some distance from it to leave a flame-space between it and the said pipe A.

The mixing-chamber C extends across to all 75 the burners, and at the top thereof are flanged openings $c c c$. In these openings are perforated burner-plates c' , which seat in the openings a little below the outer flange c^2 , as shown in Fig. 4. A flat plate H is pivoted at 80 one side of the burner and lies flat upon the flange c^2 , thus effectually closing the burner-opening c . By sliding the said plate laterally more or less an opening of greater or less size is made for the escape of gas from the 85 chamber C.

A duct, gutter or channel I extends from one burner-opening to another over the mixing-chamber C, as shown in Fig. 5. This channel or duct serves as a path for vapor to 90 travel in and ignite one burner from another, thus facilitating the transfer of ignited vapor from one burner to another.

The plate H is formed with a groove or hollow h on its bottom at one side, so that when 95 the said plate is moved to uncover a portion of the opening c , as shown in Fig. 4, the opposite side of the plate overlaps and directs gas into the channel, which, by reason of its gravity, flows along the channel to the next 100 burner-opening.

J are small perforations through which gas escapes in jets when the burner is in operation and burns about the generator op-

posite the openings to maintain the burner at a vaporizing condition.

In operation, the burner-opening *c* nearest the generator being opened by sliding away the covering-plate *H*, the valve *a* is opened and gasoline escapes from jet-orifice *a'* through the induction-tube *B* into chamber *C*, the walls of which chamber are so constructed as to conduct the gasoline to duct *D*, whence it runs to the absorbent material in initial starting-trough *E*. A lighted match or taper is applied to or through a suitable lighting-hole near the base of the perforated tube *G* about pipe *A*, and by reason of the vapor evolved from the light hydrocarbon thus introduced the flame will be immediately communicated to the gasoline at the surface of the absorbent material in trough *E*, and ignition instantly follows. A blue flame will then fill the chamber formed by the perforated tube *G* and heat the ducts *a a* and upper part of the supply-pipe. These parts quickly attain to a vaporizing condition, and vapor then issues from the orifice *a'*, and, passing through the inducting-tube *B*, entrains air in the usual manner. The vapor and air thoroughly mixing in said chamber *C* escapes at the unobstructed burner-opening near the generator in a commingled state, but for convenience of this description and claims will be spoken of as "vapor," and is ignited by the fire from the perforated tube, which remains burning until all the gasoline that is drained into the absorbent is consumed. When it is desired to ignite the gas at the next burner the cover *H* to that burner is opened a little way, as shown in Fig. 3. This places the hollow portion of the cover in such relation as to direct some of the escaping gas into the duct or gutter *I* toward the ignited burner. The gas being heavier than air it will travel by gravity in the channel to the ignited burner, and flame will flash over and pass through the narrow space between the cover and the burner-plate and will be communicated to the escaping gas at the other side of the plate. The space between the perforated burner-plate and the regulating-cover *H* will admit of flame communication but is too small to admit of continued combustion therein.

By reason of the absorbent material in the trough *E* soaking and holding the gasoline from the sides of the trough the combustion is more gradual and does not increase to an annoying extent as the walls of the trough become hot. Again, by having the gasoline discharge into the trough near its top the gasoline is quickly manifested at the surface of the absorbent and consequently is ready for ignition at once.

The valve *F* may be opened to produce and maintain a small fire to keep the vaporizing portions in a heated condition over periods in which the operation of the burner is not desired, and in this way the burner may be kept ready for full operation at any time. If desired, the burner may be initially heated

as well as maintained in a heated condition by means of this valve by simply opening the valve to a desired point and igniting the asbestos.

The manner of conducting air to the induction-tube *B* by the lateral ducts *b b* protects the gasoline or vapor escaping from valve-orifice *a'* from the flame that issues from the tube *G*, and some such protection might be considered an essential to this form of burner.

The burner-plate herein referred to may have any suitable shape or form, whether it be as here shown or in the form of a cone or any other equivalent construction.

The plate or cover *H* operates practically as a valve to control flow of vapor from a burner to the duct *I*, and is so considered and referred to herein. The flame area of the burner also is controlled by said cover or valve, as the cover may be more or less opened, as preferred.

Having thus described our invention, what we claim is—

1. A plurality of burners, a mixing-chamber common to said burners, a duct leading from burner to burner, and a plate on one of said burners to regulate the flame area and deflect vapor into said duct, substantially as described.

2. A mixing-chamber and a series of two or more burner-openings in said chamber, a duct leading from one burner to another and each burner provided with a plate to deflect vapor into said duct and to regulate the flame area of said burner, substantially as described.

3. A plurality of burners and vapor-ducts between said burners and valves for said burners constructed to govern the flame area and the flow of vapor in the said ducts, substantially as described.

4. In a vapor-burner, a generator, a mixing-chamber, an induction-tube entering said chamber, a device for initially heating the said generator, a shield encompassing the mouth of said induction-tube where it enters the mixing-chamber to protect the air and vapor inflow from the flame of said initial heating device, and a vapor-inlet through said shield, substantially as set forth.

5. In a vapor-burner, a generator and a mixing-chamber and an induction-tube for said mixing-chamber, a device for initially heating said generator, a shield about the mouth of said induction-tube to protect the air and vapor inflow from the flame of the said initial heating device and a passage for oil from said induction-tube to said initial heating device, substantially as set forth.

6. In a vapor-burner, a generator provided with a controlling-valve, a device for initially heating the said generator and an induction-tube and a flame-excluding oil-duct arranged to form an oil-passage from the orifice of said valve to the said initial heating device, the space between said valve-orifice and the induction-tube being provided with a shield to

prevent ignition of the oil from the initial lighter, substantially as set forth.

7. In a vapor-burner, a generator, a mixing-chamber, an initial heating device, an induction-tube for the mixing-chamber and a flame-excluding air-passage about the mouth of said induction-tube constructed to conduct the air required by said tube from a point distant from said mouth, substantially as set forth.

8. The burner described having a vapor expanding or mixing chamber with an induction-tube at its side for the vapor and air and a subsidiary burner at the side of the mixing-chamber contiguous to said induction-tube, and a vapor-generator exposed to said subsidiary burner, in combination with a device for initially heating said generator, and a shield encompassing the entrance to the induction-tube and separating the same from the said subsidiary burner and from said initial heating device, substantially as set forth.

9. A vapor-stove comprising a suitable supply-tank, an expansion or mixing chamber having a burner-cap and an induction-tube extending into said chamber, a shield for the induction-tube encompassing the entrance to said tube and apart therefrom to admit air and prevent escape and ignition of vapor from about said entrance, an initial burner arranged wholly outside of said shield and separated from the mixing-chamber thereby, the fluid-supply pipe leading from the fluid-tank, the vapor-controlling valve extending through said shield immediately in front of the entrance to the induction-tube, substantially as set forth.

10. In a vapor-stove, a supply-tank having a suitable outlet, in combination with the burner having an expansion or mixing chamber closed at its bottom and sides and provided with an induction-tube extending centrally into said chamber and about midway of the height of said chamber, a shield for said induction-tube closed across its top and bottom to prevent upward suction and draft across the mouth of said tube, a fluid-supply pipe leading from the fluid-supply tank and a valve projecting through said shield to control the flow of vapor from said pipe to said induction-tube, substantially as set forth.

11. In a vapor-stove an expansion or mixing chamber for the burner closed at its bottom and sides and having a burner-cap across its top, and a vapor-induction tube projecting into said chamber about midway between the bottom and top thereof, a shield encom-

passing the mouth of said vapor-induction tube from above the same and extending down directly in front thereof and apart from 60 said opening, and an induction-valve projecting through said shield, substantially as set forth.

12. In a vapor-stove, an expansion or mixing chamber, for the burner, a vapor-induction tube projecting into said chamber and open at both ends, a starting-burner and means to supply the burning fluid thereto, a shield for the induction-tube protecting the mouth of the induction-tube from above and 70 extending thence downwardly across the outer opening of said induction-tube and distant therefrom, said shield also extending between said induction-tube and the initial burner and wholly separating one from the 75 other, substantially as set forth.

13. The combination of a fluid-supply tank, a main burner, a mixing-chamber on which said burner is mounted, a vapor-induction tube leading into said chamber at its side, an 80 initial burner, a vapor jet or nozzle supported above said initial burner and in line with said induction-tube, a main fluid-supply pipe arranged within the influence of the heat from the main and initial burners and having a 85 duct communicating with the vapor jet or nozzle, a main pipe extending from the tank to the supply-pipe, a branch duct leading from the main pipe to the initial burner, a controlling-valve therein, and a shield for screening 90 the vapor-jet from the initial burner; substantially as set forth.

14. The combination of a fluid-supply tank, a main burner, a mixing-chamber on which said burner is mounted, a vapor-induction 95 tube leading into said chamber at its side, an initial burner, a vapor jet or nozzle supported above said initial burner and in line with said induction-tube, a main fluid-supply pipe arranged within the influence of the heat from 100 the main and initial burners and having a duct communicating with the vapor jet or nozzle, a main pipe extending from the tank to the supply-pipe, a branch duct leading from the main pipe to the initial burner, a controlling-valve therein and a shield for screening 105 the vapor-jet, substantially as set forth.

Witness our hands to the foregoing specification this 30th day of March, 1893.
